IRONING DEVICE

Joseph Kinzelman, Northbrook, Ill.

Application June 2, 1954, Serial No. 434,003

4 Claims. (Cl. 29—128)

The present invention relates to ironing devices, and more specifically to rollers for use in ironing devices.

The ironing devices presently known to the art are generally of two types. The first type of ironing device uses a roller which is rotated at a uniform rate and is disposed adjacent to an ironing shoe which may be moved into contact with the roller. The second type of ironing device uses a plurality of rollers in contact with a larger drum, the drum being rotated at a rate slightly less than that of the rollers. In the first type of ironing device, heat is supplied to the fabric being ironed through the shoe, the fabric being drawn between the shoe and the roller by friction between the fabric and the roller. In the second type of device, the fabric is drawn and stretched between the rollers and the drum, and heat is supplied to the fabric through the drum.

In both types of ironing devices there is difficulty in maintaining the cylindrical shape of the rollers. Continued use tends to bunch the material used in the construction of the roller at one end of the roller giving it an irregular or generally conical shape. This is partly due to the fact that the roller must present a resilient surface to the fabric, since many fabrics which are to be ironed contain protrusions, such as buttons. They also compact until they have lost their resilience. A second difficulty arises from the fact that organic materials have been found to be necessary in the rollers presently used in order to provide sufficient resilience and the organic materials char because of the heat required in ironing, thus limiting the useful life of the rollers.

It is an object of the present invention to provide an ironing device which utilizes a roller which presents a resilient surface to the fabric to be ironed and will be substantially free from charring and compacting.

It is also an object of the present invention to provide an ironing device with a resilient roller which will maintain its cylindrical form through extensive use.

A further object of the present invention is to provide a roller adapted to be used in an ironing device which neither chars nor loses its cylindrical form with extensive use.

Further objects and advantages of the present invention will be readily apparent to the man skilled in the art from a further reading of the present disclosure and claims, particularly when viewed in the light of the drawings, in which:

Figure 1 is a side elevational view of an ironing device embodying the present invention;

Figure 2 is a side elevational view of an ironing device constituting a second embodiment of the present invention;

Figure 3 is a transverse sectional view of a roller suitable for use in both of the embodiments shown in Figures 1 and 2;

Figure 4 is an enlarged fragmentary sectional view of the roller shown in Figure 3; and

Figure 5 is an enlarged fragmentary sectional view of

2

the ironing device illustrated in Figure 1 showing a fabric in the process of being ironed.

In the type of ironing device illustrated in Figure 1, a roller 10 is disposed on a shaft 12 and supported by means partially illustrated at 14. The shaft 12 and the roller 10 are free to rotate relative to the support means 14 and are supplied with rotational power by a conventional motor. An ironing shoe 16 is disposed adjacent to the roller 10 by means of conventional design partially illustrated at 18. The space between the shoe 16 and the roller 10 may be manually controlled to permit the operator to insert a fabric 20 between the roller 10 and the shoe 16, and to control the pressure exerted by the shoe 16 and roller 10 upon the fabric 20. The shoe 16 may also be supplied with a source of heat which is conventional in the art and has not been illustrated. The three heat methods most commonly used to heat the fabric are electrical heating, gas heating and steam heating of the shoe 16.

The roller 10 is constructed with a cylinder 22 of rigid construction and the shaft 12 is disposed on the axis of the cylinder 22. The cylinder 22 is generally constructed of metal, such as iron or steel. A plurality of layers of different materials 24, 26, 28 and 30 are tightly wound about the cylinder 22 and provide the roller 10 with its resilient surface. The layer 24 is immediately adjacent to the cylinder 22 and is constructed of canvas. Immediately adjacent to the layer 24 of canvas is a layer 26 of wire cloth, such as is commonly used for house insect screens. The outer layer 30 is cloth which may be asbestos or cotton cloth. If cotton cloth is used as the outer layer 30, an asbestos cloth layer 28 may be inserted between the wire cloth 26 and the outer layer 30.

As will be seen from Figure 4, the layer 24 of canvas is secured to the cylinder 22 by a layer of glue 32 and overlaps the beginning of the first turn of the adjacent layer 26, the first turn being indicated by the reference character 34. The first turn 34 of the wire cloth of layer 26 may be cemented, or otherwise secured, between the turns of canvas in layer 24, thereby being prevented from rotating relative to the cylinder 22. A similar construction may be used to secure the outer layer 30 of cloth to the last wire layer 26.

A desirable construction for the roller 10 utilizes a hollow steel cylinder with a diameter of approximately five inches, although other diameters are equally satisfactory. Layer 24 consists of approximately 1½ turns of canvas glued to the cylinder 22, layer 26 consists of approximately 10 turns of wire cloth, and outer layer 30 consists of 2 to 3 turns of asbestos or cotton cloth.

As is illustrated in Figure 5, the roller 10 presents a resilient surface to the cloth 20 which passes between the roller 10 and the shoe 16. A button 36 is illustrated compressing the wire cloth of layer 26 of the roller 10 as it passes between the roller 10 and the shoe 16. It is to be noted, that the layers 30 of cloth do not become substantially compressed, and that the resiliency of the roller 10 is supplied essentially by the wire cloth in layer 26. It is also to be noted that the wire cloth in layer 26 is not an organic material and will not char from continued subjection to heat, thereby giving the roller 10 a longer life than the rollers heretofore known to the art.

The layer 30 of cloth is longer than the length of the cylinder 22 and overlaps the ends of the cylinder 22. A draw cord 38 is slidably disposed within a channel formed at the end of the cloth layer 30 and draws the cloth layer 30 tightly about the roller 10 in a manner conventional in the art.

Figure 2 illustrates a second embodiment of the present invention. In this type of ironing device, a drum 38 of a relatively large diameter and constructed of rigid heat conducting material, such as sheet metal, is disposed ad-

ja⁵cent to a plurality of rollers 40 of smaller diameter, usually three in number. The drum 38 rotates at a rate slightly less than the rotation rate of the rollers 40. As a result, the fabric to be ironed 42 is drawn between the rollers 40 and the drum 38. A feeding plate 44 may be disposed adjacent to the input side of the ironing device to support the fabric 42 as it approaches the drum 38 and rollers 40. The rollers 40 are constructed identically with the rollers 10 illustrated in the first embodiment of the invention, and hence the rollers 40 will not be further described. As in the first embodiment of the invention, the rollers 40 present a resilient surface to the fabric 42 which passes between the rollers 40 and the drum 38, are constructed of materials which will not char due to heat supplied to the drum 38, and also will retain their cylindrical shapes longer and under more severe conditions than the rollers theretofore known to the art.

A man skilled in the art will readily devise many modifications and improvements within the scope of the invention disclosed herein, and hence it is intended that the scope of this invention be not limited by the foregoing disclosure, but only by the appended claims.

What is claimed is:

1. A roller adapted to be used in an ironing device comprising a rigid cylinder, a first layer consisting of canvas wound about the cylinder and attached thereto, a second layer consisting of a plurality of turns of screen wire cloth tightly wound about the first layer and connected to said canvas, and an outer layer consisting of a plurality of turns of cloth comprising inorganic materials 25

rality of turns of screen wire cloth tightly wound about said first layer, the first $\frac{1}{3}$ turn of said second layer being overlapped by the last $\frac{1}{3}$ turn of the first layer and secured to said last $\frac{1}{3}$ turn of the first layer, and an outer 10 layer consisting of 2 to 3 turns of cloth constructed of non-metallic materials.

3. An ironing device comprising a roller including a rigid cylinder, a first layer consisting of canvas secured about said cylinder, a second layer consisting of a plurality of turns of screen with cloth tightly wound about said first layer and connected to said canvas, and an outer layer consisting of a plurality of turns of asbestos cloth tightly wound about the adjacent layer.

4. In an ironing device, a roller comprising a rigid cylinder, a first layer comprising canvas wound about and attached to said cylinder, a plurality of layers comprising a plurality of turns of wire cloth tightly wound about said first layer, the inner end of said wire cloth being overlapped by a partial turn of said canvas, and an 15 outer cover comprising a plurality of turns of cloth tightly wound about said plurality of turns of wire cloth.
